UNITED STATES PATENT OFFICE.

THOMAS EVANS, OF PITTSBURG, PENNSYLVANIA, ASSIGNOR TO THOMAS EVANS & CO., OF SAME PLACE.

LAMP.

SPECIFICATION forming part of Letters Patent No. 313,192, dated March 3, 1885.

Application filed April 30, 1884. (No model.)

To all whom it may concern:

Be it known that I, THOMAS EVANS, a citizen of the United States, residing at Pittsburg, county of Allegheny, State of Pennsylvania, have invented or discovered a new and useful Improvement in Lamps; and I do hereby declare the following to be a full, clear, concise, and exact description thereof, reference being had to the accompanying drawings, 10 making a part of this specification, in which, like letters indicating like parts—

Figure 1 is a view in side elevation of a lamp embodying my invention. Fig. 2 is a sectional view of a mold for forming the lamp-body, the 15 lamp-body being shown in section within the mold. Fig. 3 is a top plan view of the mold.

My invention relates to the construction of the body of that class of lamps which are supported while in use in the rings or cups of a 20 bracket or chandelier.

The rings or cups which are attached to brackets or chandeliers for holding lamps are made of two sizes, and heretofore the lamp-bodies have been made of corresponding sizes 25 with a single seat fitting the ring or cup; consequently on the breakage of either the ring or lamp, it is necessary that a ring or lamp of the same size should be obtained, which can- 30 not always be conveniently done.

The object of my invention is to so construct the lamp-bodies that they will fit both sizes of rings or cups; and to this end my invention consists in the construction of a lamp-body, 35 all as more fully hereinafter described and claimed.

In the drawings, A indicates a lamp-body whose general outline is the same as those now in general use having the usual perforated projection, a, for the attachment of the burner 40 and the filling-opening b. In place, however, of forming one seat on the under tapering side of the body for the ring or cup, I form two of

such seats, c and d, of different sizes, as shown, the seat c being adapted to fit in the larger or No. 3 ring or cup, and the seat d to fit the 45 smaller or No. 2 ring or cup, thereby adapting the body to fit either size of ring or cup.

B represents a hollow mold made of three parts, e, e', and e'', as is usual, hinged together, as shown at f f', and provided with handles h 50 and h'. This mold when in use rests upon a bed, C, which is provided with the projection k under cut at its periphery, and the mold is correspondingly recessed on its under side so as to fit around this projection when closed. 55 This top of this projection is constructed on its upper surface so as to form the bottom of the lamp. On the inwardly-tapering sides of the mold are formed the grooves l l', in which during the molding of the lamp-body are 60 formed the seats cd for the ring or cup.

I am aware that it is not new to form lamp-bowls with a single seat, the portion of the bowl below such seat being made tapering, as shown in Patents Nos. 160,848 and 123,379; 65 and I am also aware that lamp-bowls have been made with two ornamental curved beads on their lower portions, such beads not being designed, spaced, or constructed to fit standard sizes of supporting rings or cups, as is the 70 case in the bowl described and claimed in this application.

I claim herein as my invention—

A lamp-body, A, having the seats c and d suitably spaced and constructed to fit the different standard sizes of rings or cups of a chandelier or bracket, substantially as set forth.

In testimony whereof I have hereunto set my hand.

THOMAS EVANS.
